DECORATIVE DISPLAY BORDER OR SIMILAR ARTICLE

Louis Marcus, Newton, Mass.

Application November 2, 1956, Serial No. 43,647

Term of patent 14 years

(Cl. D80—1)

Fig. 1.

Fig. 2.

Fig. 3.

Fig. 1 is a top plan view of a decorative display border or similar article showing my new design;
Fig. 2 is a perspective view thereof, and
Fig. 3 is a sectional view taken on the line 3—3 of Fig. 1.

I claim:

The ornamental design for a decorative display border or similar article, substantially as shown.
